James Pitzler

UNITED STATES PATENT OFFICE.

JAMES PITZLER, OF NEW YORK, N. Y.

IMPROVEMENT IN NEEDLE-WRAPPERS.

Specification forming part of Letters Patent No. 117,324, dated July 25, 1871.

To all whom it may concern:

Be it known that I, JAMES PITZLER, of the city of New York, in the county and State of New York, have invented certain Improvements in Needle-Wrappers, of which the following is a specification:

This invention relates to an improved mode of fastening to needle-holders or to needle-wrappers the strip of cloth, silk, or other fabric into which are to be stuck the needles; and it consists of the needle-holder or needle-wrapper being made with cuts or slits crosswise or at right angles with the direction in which the needles are to be stuck thereon, and passing both ends of the strip of cloth, silk, or other fabric through said slits, whereby the fabric is thrown forward and presents a perfect cushion for sticking the needles.

In another application (A) I have described the mode of making an improved needle-wrapper or package in which there is a needle-holder. I propose here to state how the cloth or other fabric is fastened to such a needle-holder, dispensing with paste, cement, rivets, clamps, &c., and enabling the manufacturer to make the said holder of tin-foil if thought fit.

Figure 1 is a front view of a sheet of paper or tin-foil, cut, ready to make my improved needle-holder. Fig. 2 is the same seen from the side. Fig. 3 is the needle-holder finished. Fig. 4 is a front view and Fig. 5 a side view of a modification of my mode of fastening the needle-cloth to the tin-foil or paper, and Figs. 6 and 7 are similar figures of another modification thereof.

To make my improved needle-holder a piece of paper or tin-foil is cut three times wider than the desired width for the finished holder and of the proper length therefor, and the top is cut in any desired shape to make a finish on the flap. Two or more slits, C C', are now cut in the central part A crosswise to the length thereof, and of the proper length to correspond to the width of the strip of fabric upon which the needles are

to be stuck. A piece of cloth, silk, or other fabric, B, is passed or woven in through the slits C C', passing in front of the part between two slits, and having its two ends extending top and bottom behind, as seen in Fig. 2. The two flaps A' and A'' are folded back and doubled over one another, so that the holder will be three thicknesses and have the appearance seen in Fig. 3.

The advantage of this mode of securing the cloth B to the needle-holder or wrapper will be better understood by inspecting Figs. 2, 5, and 7, where it plainly shows how the cloth, in passing through the crosswise slits, is bulged forward, and presents the proper shape for the needles being stuck therein. The strip of cloth may be of the full width of the needle-holder, and the two ends, top and bottom, need not be doubled under, but may be left flat, which makes the holder all of the same thickness—a decided advantage for packing or for sliding into an outer wrapper or case. In the case of Figs. 4, 5, 6, and 7, where the cloth is made to pass forward twice or three times, the needle, by being stuck therein, effectively fastens itself and the cloth to the wrapper A in a neat and solid manner.

I do not claim having originated the idea of fastening the cloth upon which needles are stuck to a needle-holder without the use of paste, rivets, clamps, &c., as I know this has already been done; but

What I do claim as my invention, and desire to secure by Letters Patent of the United States, is—

The needle-holder A, having the cloth or other fabrics B secured thereto by said cloth being passed through slits cut crosswise to the length of the needles, which are stuck upon said cloth, substantially as set forth.

JAMES PITZLER.
